UNITED STATES PATENT OFFICE

WILLIAM F. GROENE, OF CINCINNATI, OHIO, ASSIGNOR TO THE R. K. LE BLOND MACHINE TOOL COMPANY, OF CINCINNATI, OHIO, A CORPORATION OF DELAWARE

LATHE-OILING MECHANISM

Application filed June 4, 1928. Serial No. 282,672.

My invention relates to lathe oiling mechanisms whereby a simple arrangement provides for oil at all moving parts of the apron, slide and cross slide, with a reservoir for settling and a flow of oil over the driving gearing from a single source of pressure located in a sump.

It is my object to provide for an oil reservoir in the slide, which receives oil through suitable channels from a pump located at the lower edge of the apron, from which reservoir the oil travels along the feed screw of the cross slide, so as to lubricate the ways for the slide, and thence spills down over the enclosed drive gear assembly in the apron to the sump. From the sump the oil is pumped to delivery channels in the apron, whence it is piped by means of tubes or passageways to the various shaft bearings, and to grooves in the ways for the cross slide. Finally it drips from the cross slide ways grooves into the reservoir, thus completing a cycle, with the reservoir serving as a collecting basin, and in which a level of oil is maintained at a proper height to spill back again as above noted, by maintaining a proper quantity in the system.

Among other features I provide for oiling the ways for the slide by capillary wood blocks exposed to the flow about the feed screw of the cross slide, and I maintain the gearing in a dripping flow of oil at all times.

I accomplish my objects by that certain construction and arrangement of parts to be hereinafter more specifically pointed out and claimed.

In the drawings:

Figure 1 is a section taken on the line 1—1 of Figure 2 with the cross slide removed.

Figure 2 is a detail front elevation of the apron, slide and cross slide of a lathe.

Figure 3 is a top plan view of the apron by itself.

Figure 4 is a detail section taken on the line 4—4 of Figure 3.

Figure 5 is a top plan view of the slide with the cross slide and the feed screw therefor removed.

Referring to the drawings, it will be noted that I have indicated at the bed of the lathe at

1, having ways 2, and 3, for supporting the slide 4. The slide has a pair of channels 5, 5, located along the ways 6, 6, for the cross slide.

These channels have tubular passages extending to the ways as indicated at 7, and 55 also have overflow notches 8 in their sides, which permit oil to flow by gravity into a reservoir 9 formed in the slide.

This reservoir has a bottom plate 10, which is removable for cleaning, and its central 60 portion is deeper than the rest.

The oil stands in this reservoir at a level indicated by the line A, and wood blocks 11, are located in the slide, so as to come into contact with the oil in the reservoir, and by 65 capillary action provide for a film of oil on the ways for the slide.

The oil flows along from the level A, through the hole 14 in the slide that accommodates the feed screw 12 for the cross slide 70 and the cross slide 13, as actuated by the feed screw, is so located as to close the tops of the channels 5, 5, in the slide.

The apron cavity lies beneath the portion of the slide where the hole 14 terminates, so 75 that oil flowing along the feed screw drips down over the gears in the apron.

Located in the apron 15, is a pump casing 16, having a plunger 17 therein, that is moved up and down by means of a cam or eccentric 80 18. Any suitable type of pump would serve my purpose.

A removable cap 19, located over a hole in the bottom of the apron serves as a sump for the pump, and the oil is ejected by the 85 pump through a pipe 20.

The pipe 20 extends to a passageway 21 in the apron, which leads to a long channel 22 in the top of the apron.

The channel 22, by means of passageways 90 extending therefrom as indicated at 23, provides lubricant to the shaft bearings of the drive, and also supplies oil to a small channel at one end of the apron as indicated at 24, by means of a channel 25 in the top of the 95 apron that communicates with both the channel 22 and said channel 24.

The channel 24 by means of passageways 26, lubricates the several shaft bearings at the outside face of the apron. The drip of 100

oil onto the gear drive system maintains the shafts for said gears with proper lubricant at the intermediate portion of the apron.

The channels in the top of the apron are maintained closed at the top by means of the slide located thereon, and two passages 27 in the slide conduct lubricant from the main channel 22 in the apron to the two channels located in the top of the slide along side of the reservoir.

As so constructed, it will be noted that oil under pressure is delivered to the several shaft bearings, is delivered by gravity or capillary action to the several ways, and drips over the gear assembly in the apron, all from a single pump and by means of a system which includes a collecting reservoir near the top of the system, wherein chips or solid matter will be eliminated by gravity and intermittent cleaning when required.

Having thus described my invention, what I claim as new and desire to secure by Letters Patent, is:

1. An oiling system for lathes, comprising a pump for oil located in the apron, means for delivering oil therefrom to the cross slide ways, and to a reservoir located in the slide, and for draining back from the reservoir by gravity flow over the gear assembly in the apron.

2. An oiling system for lathes comprising a pump for oil located in the apron, a channel in the apron to which said oil is delivered by the pump, passageways from said channel directed to the shaft bearings, passageways from said channel directed to the top of the slide, a reservoir in the slide, and passageways from the reservoir delivering oil by gravity to the interior of the apron above the gear assembly therein.

3. An oiling system for lathes comprising an oil pump in the apron, channels in the slide adjacent the cross slide ways to which oil is delivered by the pump, passages therefrom to the cross slideways, passages therefrom delivering oil to a reservoir located in the slide, and passages from the reservoir to the top of the apron for delivering oil by gravity from the reservoir to the interior of the apron.

4. An oiling system for lathes comprising an oil pump in the apron, channels in the slide adjacent the cross slide ways to which oil is delivered by the pump, passages therefrom to the cross slideways, passages therefrom delivering oil to a reservoir located in the slide, and passages from the reservoir to the top of the apron for delivering oil by gravity from the reservoir to the interior of the apron and capillary blocks receiving lubricant from the reservoir and engaging the ways for the slide.

5. An oiling system for lathes comprising an oil pump in the apron, channels in the slide adjacent the cross slide ways to which

oil is delivered by the pump, passages therefrom to the cross slideways, passages therefrom delivering oil to a reservoir located in the slide, and passages from the reservoir to the top of the apron for delivering oil by gravity from the reservoir to the interior of the apron and passages communicating with the delivery of the said pump, extending to the shaft bearings in the said apron.

6. An oiling system for lathes comprising an oil reservoir and a pump, another oil reservoir affixed to the slide and travelling therewith, connections from the said pump to deliver oil along the said slide, means for lubricating the cross slideways on said slide and means for lubricating the main slideways on the base, and a passageway in said slide for returning oil to said first named reservoir.
